US00D746300S

(12) **United States Design Patent**
Aldamiz Echevarria et al.

(10) **Patent No.:** **US D746,300 S**
(45) **Date of Patent:** **** Dec. 29, 2015**

(54) **DISPLAY SCREEN WITH GRAPHICAL USER INTERFACE**

(71) Applicant: **Chicisimo S.L.**, Bilbao (ES)

(72) Inventors: **Gabriel Aldamiz Echevarria**, Bilbao (ES); **David Bolufer**, Bilbao (ES)

(73) Assignee: **Chicisimo S.L.**, Bilbao (ES)

(**) Term: **14 Years**

(21) Appl. No.: **29/465,483**

(22) Filed: **Aug. 28, 2013**

(51) LOC (10) Cl. **14-04**

(52) U.S. Cl.

USPC **D14/485**
